UNITED STATES PATENT OFFICE.

CORNELIUS A. FOLLY, OF BOONTON, NEW JERSEY.

BOTTLE-HOLDER.

1,243,500.

Specification of Letters Patent.

Patented Oct. 16, 1917.

Application filed June 20, 1917. Serial No. 175,770.

To all whom it may concern:

Be it known that I, CORNELIUS A. FOLLY, a citizen of the United States, and a resident of the city of Boonton, in the county of Morris and State of New Jersey, have invented a new and Improved Bottle-Holder, of which the following is a full, clear, and exact description.

This invention relates to a bottle holder 10 and particularly to a holder for milk bottles, and has for an object the provision of improved construction whereby as the bottle is delivered to a customer it is automatically locked in the holder against removal until 15 the customer has opened a door or window adjacent thereto.

Another object in view is to provide a holder for milk bottles which may be arranged adjacent a door or window, or a 20 number of holders superimposed for receiving any desired number of bottles and locking the same against removal until the customer has opened the door or window.

A further object of the invention is the 25 provision of a holder, which is made of a minimum number of parts, but which will receive a bottle and hold the same in a locked position.

A still further object of the invention is 30 the provision of a holder, which when the bottle is positioned therein, presents such a structure as to accommodate the expanded milk when frozen, and to prevent removal by an unauthorized person.

35 In the accompanying drawings,

Figure 1 is a sectional view through a door, and a holder embodying the invention, two bottles being shown in connection therewith;

40 Fig. 2 is a sectional view through Fig. 3 on line 2—2;

Fig. 3 is a top plan view of the holder shown in Fig. 2;

Fig. 4 is a sectional view through Fig. 3 45 on line 4—4;

Fig. 5 is a detail perspective view of a locking trough embodying certain features of the invention;

Fig. 6 is a detail perspective view of a 50 locking pawl disclosed in certain features of the invention;

Fig. 7 is a slightly modified form of the locking trough as shown in Fig. 5.

Referring to the accompanying drawing 55 by numerals, 1 indicates a door which is supported in any suitable way, as for in-

stance, by hinges 2, so as to swing inwardly, or away from the holder 3, whereby the bottles 4 and 5 may be pulled from the holder 3 toward the position occupied by 60 the door 1. It will be noted that the bottle 4 rests on the door sill and also interlocks with the holder 3, and that bottle 5 rests on the holder 3 and is arranged so that the upper end will interlock with another 65 holder above the same. Any desired number of holders 3 may be used adjacent door 1, or if it is not convenient to employ the same adjacent a door, the holders may be arranged adjacent a window, so that when 70 the window is raised or moved to one side the bottle may be pulled inwardly in a horizontal plane.

The idea is to provide means whereby the delivery man may force the bottles into 75 the holders in a horizontal plane from the outside, but no one can remove the same from the outside, while the customer may open the door or window and remove the bottles inwardly.

The holder 3 is made from a minimum 80 number of parts and with only one movable part, namely the locking pawl 7. As shown in the drawing there are three parts which are preferably cast and a rivet 8 for securing 85 two of the parts together, namely the trough 9 and the section 10 of the body 11. Section 10 as shown in Fig. 4 is raised above the remaining part of the body whereby the space 12 is provided which will permit 90 the frozen milk to expand without breaking any parts. The beveled ends 13 and 14 of the section 10 will guide the frozen milk away from the bottle, said beveled ends being assisted by the beveled sides 95 15 and 16 of the trough 9. It will be noted that the body 11 has a web or raised portion 10 having beads 17 and 18, on which the upper bottle 5, either of a full sized variety or smaller variety is adapted to rest. Along 100 the edges of the body 3 are side members 19 and 20 which extend above and below the body approximately the same distance, said members 19 and 20 being provided with suitable apertures 21 for receiving securing 105 means for holding the holder in position. When there is no bottle on the upper part of the holder an unauthorized person may remove the securing means above the body 3, but when there is a bottle in the holder 110 below in the body 3 said bottle would be in the way of the unauthorized person from

attempting to remove the securing members from the lower apertures 21. Depending flanges 22 and 23 are provided on the body 11 as shown in Fig. 4 for guiding the bottle 5 and for preventing an unauthorized person from being able to remove the locking pawl from out of its correct position as shown in Fig. 2, where in case a knife or other thin instrument is inserted, said knife or instrument will be forced to engage the pawl in the notch or slot 24 and thereby to prevent any lifting of the pawl. A stop or projection 25 is made on the upper end of the pawl, said stop or projection engaging 10 part of the trough 9 as shown in Fig. 2 for limiting the downward swinging movement of the pawl. Pawl 7 may be made in any suitable manner, as for instance by casting, and when formed it is preferably formed 15 with integral journaled extensions 26 and 27 fitting into the notches 28 and 29 in trough 9, there being a slot or aperture 30 for allowing the free movement of the pawl when the bottle is being inserted. By providing the trough 9 separate from the body 11, trough 9 may be cast if desired as well as the body 11 and pawl 7, and at the same time presenting a stop and a free pivotally mounted pawl. It will be noted from Fig. 20 25 that the pawl engages the bottle and cannot be raised by a knife or other instrument by reason of the engagement of the bottle and cannot be swung in the opposite direction by reason of the extension 25, so that 30 the only way that the pawl can be removed 35 to a position out of the way is by moving the bottle inwardly toward the door 1 and through the doorway, which cannot be done until the door has been opened so that an 40 unauthorized person cannot remove the bottle.

The construction of the trough 9 as shown in Figs. 4 and 5 is preferable as it gives a better spreading action to the frozen milk 45 when expanding and also acts better in a mold when casting, but if desired a slightly modified form can be used, as for instance, trough 31 as shown in Fig. 7, with the pointed or double beveled ends 32 and 33.

50 In forming the various parts they have been constructed so as to be cast in workable condition, whereby all machine work is eliminated, except the provision of the apertures 21 and the rivet 8, which must be put 55 in position after the trough and body 11 have been assembled.

What I claim is:

1. In a bottle holder of the character described, a body provided with a pair of depending flanges, between which the upper end of the bottle is positioned when the holder is in use, and a locking pawl connected with the body and fitted into the up-

per part of said bottle, said locking pawl being provided with a slot for preventing unauthorized lifting thereof. 65

2. In a holder of the character described, a body provided with a pair of depending flanges, between which the upper end of the bottle is designed to be positioned by the deliveryman, and a pair of side members formed with apertures for receiving securing members, a trough connected with said body between said flanges, said trough having a notch, and a locking pawl provided with journal members pivotally mounted in said notch for preventing removal of said bottle in one direction. 70 75

3. In a holder of the character described, a body formed with side members extending above and below the holder, and a raised section or platform for receiving bottles, said body also being provided with a pair of depending flanges on the under surface spaced a proper distance apart for receiving the upper part of a bottle, said side members being formed with openings for receiving securing members and means connected with said raised section for locking the lower bottle to the holder. 80 85 90

4. In a milk bottle holder of the character described, a body formed of side members having openings for receiving securing members, and a raised central section providing space for the milk when frozen, a trough arranged in said section formed with beveled sides for directing the milk as it moves during the freezing thereof, and a locking member carried by said trough for engaging the bottle arranged beneath said 100 section.

5. In a milk bottle holder of the character described, a body provided with a raised central section, and a pair of depending flanges on the lower surface between which the bottle is adapted to be positioned, a trough connected to said body on the lower surface of said raised section, said trough having a slot and a pair of journal receiving apertures, and a pawl fitted into said slot having journal members extending into said apertures and an extension adapted to strike the trough so as to limit the pivotal movement in one direction, said pawl having a notch for receiving an instrument inserted with the intention of raising the pawl. 105 110 115

6. A milk bottle holder comprising a body, a trough formed with a notch in its upper face, means for securing said trough to said body so that said upper surface will be in contact therewith, and a locking pawl having journal members loosely mounted in said notch. 120

CORNELIUS A. FOLLY.
